UNITED STATES PATENT OFFICE.

WILLIAM J. RANKIN, OF MCKEESPORT, PENNSYLVANIA.

REFRIGERATING-WAGON.

SPECIFICATION forming part of Letters Patent No. 683,662, dated October 1, 1901.

Application filed October 5, 1900. Serial No. 32,098. (No model.)

To all whom it may concern:

Be it known that I, WILLIAM J. RANKIN, a citizen of the United States, residing at McKeesport, in the county of Allegheny and State of Pennsylvania, have invented certain new and useful Improvements in Refrigerating-Wagons, of which the following is a specification, reference being had to the accompanying drawings, forming part of this specification, in which—

Figure 1 is a central vertical longitudinal sectional view of my improved refrigerating-wagon, the section being taken on the line II. Fig. 2 is a horizontal longitudinal section taken on the line II II of Fig. 1. Fig. 3 is a vertical cross-section taken on the line III III of Fig. 1. Fig. 4 is a sectional view through the ice-box, illustrating the construction on an enlarged scale. Fig. 5 is a detail view showing the outlet-pipe from the pan of the ice-box. Fig. 6 is a detail view illustrating a portion of the side framing and of the adjustable shelf in the act of being dismantled. Fig. 7 is a detail view illustrating the use of 25 a lining material acting as a non-conductor of heat.

My invention relates to refrigerating-wagons; and it consists in certain features of construction relating to the manner of mounting 30 the supporting-shelves, the ice-receptacle, removable milk-churn, and other features, as shall be more fully hereinafter set forth.

Referring now to the drawings, 2 2 represent the axles of the running-gear, upon 35 which in any preferred manner is mounted the main wagon structure 3, consisting generally of a forward compartment A for the driver and rear compartment B, adapted to receive the contents for which the wagon is 40 particularly designed. In the present instance I have shown a construction adapted to be used for storing and transporting milk and cream either in bottles or in bulk, the object in view being to provide for the economical use of the interior space of the wagon, 45 so as to admit of a large number of bottles and in such a manner that they may be readily placed in position and withdrawn for purpose of delivery. To this end I have arranged 50 along each inner side of the wagon supporting-sills 4, upon which rest the platforms 5 in such a manner as to divide the height and

interior space into several separate compartments adapted to receive the boxes containing the bottles, or, as shown in Fig. 3, of sufficient height at the center to allow of the insertion of a can. These supporting-platforms 5 are provided with slats along their upper surfaces, permitting thorough ventilation and passage downwardly of the cold air from the 60 ice-box and also facilitating cleaning operation. They are also made in such a manner that by raising one side the other side may be dropped, and all the platforms may in this manner be laid upon the bottom of the wagon, 65 leaving the entire interior open and uninterrupted in case it is desired to use the wagon for any other purpose. This operation is illustrated in Fig. 6.

Between the front and back compartments 70 of the wagon extends the cross-partition 6, by which the space B is rendered practically airtight, and a portion of this partition is formed into a forwardly-projecting semicircular wall 7, having a hinged door or doors 8, the back 75 portion of an inclosed space 9 being surrounded by a similar semicircular arrangement of framework 10, having intervening open spaces permitting circulation of the cold air from the ice-box. Within the interior space 9, 80 which is of just a size to receive it, is placed a can 11, adapted to contain milk or cream in bulk, the faucet of the can projecting outwardly through the door and the packing material or curtain 12 into the front compartment A in convenient proximity to the driver, 85 so as to facilitate the withdrawal of milk from the can. Between the front and back compartment also may be located one or more doors 13, by which communication may be 90 had with the interior of the wagon, so that the bottles of milk may be taken out by the driver without the necessity of leaving his seat. Ordinarily, however, the compartment B is charged or withdrawn from through rear 95 doors 14, which may be provided, if desired, with any packing substance, so as to render them air-tight.

The ice-compartment C consists of an outer framework 15, provided at different heights 100 with air-ventilation openings 16 and false sides 17, projecting inwardly from the side of the frame, so that circulation of air through the interior spaces and around the ice, which

is placed in the compartment C, is facilitated. At the bottom is a pan 18 to collect the water as the ice melts, the pan being provided with the drip-pipe 19, leading outwardly from the 5 pan and downwardly along the side of the wagon, terminating in a double gooseneck 20, adapted to make a water seal to prevent passage of air or dust to the interior of the ice-compartment. A removable top 21 is provided for the compartment to permit of insertion of the ice, and this top should be made air-tight and, if desired, provided with means for clamping it down upon the outer framework.

15 In Fig. 7 I have shown a detail view wherein a lining material 22, of any suitable non-heat-conducting material—as asbestos, paper, fiber, &c.—is laid over the surface of the walls, top and bottom, doors, &c., by which means the 20 refrigerating action is assisted by confining the cold air and preventing passage to the interior of outside warm air. The use of such covering material in suitable thickness and arrangement will be found to be a valuable adjunct to my invention and of considerable advantage in the manner indicated.

The construction of my wagon renders it well adapted for the uses for which it is designed, and in practice I have found it to 30 give better results than any other wagon or vehicle for transporting milk that I have known, and its simplicity, economy of space, facility for loading and unloading, the ease with which it is kept clean, and the thorough 35 manner in which the downward circulation of the cold air from the ice-compartment at the top, keeping the milk cool, will be appreciated and understood by all persons accustomed to the handling or transportation 40 of milk, especially during warm weather.

Changes in the design, arrangement, and location of the various parts and elements of my invention may be made by the skilled mechanic without departing from it, since

45 What I claim, and desire to secure by Letters Patent, is—

1. In a refrigerating-wagon, a front compartment for the driver, a rear compartment having a series of removable shelves, an ice-holding chamber located in the upper portion of the rear compartment and provided 50 with air-circulation openings in its walls permitting cold air to pass downwardly therefrom into said rear compartment, a substan-

tially air-tight partition between said front and rear compartments, and a milk-can-receiving compartment provided with a substantially air-tight front wall and a ventilating back wall in communication with the rear compartment so as to permit cold air to circulate around said can, substantially as described.

2. In a refrigerating-wagon, a substantially air-tight rear compartment, a series of longitudinal supporting-sills secured along 60 the inner sides of said compartment, a series of transverse shelves removably mounted on said sills, said shelves being connected together by longitudinal slats attached thereto, an ice-holding chamber situate in the upper 65 forward portion of the rear compartment and provided with air-circulation openings in its walls permitting cold air to pass downwardly therefrom into said compartment, a drain-pipe for the ice-chamber, a front compartment for 70 the driver, a substantially air-tight partition between the front and rear compartments provided with one or more doors by which access may be had to the rear compartment from the front compartment, and a milk-can-receiving chamber provided with a substantially air-tight front wall and a ventilating back wall in communication with the rear compartment, permitting cold air to circulate 75 around the can, substantially as described.

3. In a refrigerating-wagon, a front compartment for the driver, a rear compartment having a series of shelves, an ice-holding chamber situate in the upper portion of the rear compartment and provided with air-circulation openings in its walls permitting cold air to pass downwardly therefrom into said rear compartment, a substantially air-tight partition between said front and rear compartments, a milk-can-receiving chamber provided with a substantially air-tight front wall projecting into said front compartment and a ventilating back wall projecting into the rear compartment and in communication therewith by ventilating-openings permitting 90 cold air to circulate around said can.

In testimony whereof I affix my signature in presence of two witnesses.

WILLIAM J. RANKIN.
